UNITED STATES PATENT OFFICE.

FRANK J. FRAZEE, OF OSAGE, IOWA.

AUTOMATIC STOP FOR SOUND-REPRODUCING APPARATUS.

1,409,539.

Specification of Letters Patent. Patented Mar. 14, 1922.

Application filed September 23, 1919. Serial No. 325,755.

To all whom it may concern:

Be it known that I, FRANK J. FRAZEE, a citizen of the United States, residing at Osage, in the county of Mitchell and State 5 of Iowa, have invented certain new and useful Improvements in Automatic Stops for Sound-Reproducing Apparatus, of which the following is a specification.

This invention relates to improvements in 10 sound reproduction apparatus and more particularly to an improved means for automatically stopping the motor of such an apparatus when the stylus reaches the end of the record groove.

15 One of the objects of the present invention is to provide in mechanism of the class mentioned, means for braking the motor automatically when the stylus reaches the end of the record groove and which means 20 will accomplish this result without the provision of any stop devices or other attachments to the record, to the record turntable, or to the sound box of the reproducing apparatus.

25 Another object of the invention is to provide in an apparatus of this class, a sound box rest normally yieldably supported in elevated position and designed to be depressed when the sound box is disposed 30 thereon, and means actuated automatically through depression of the said rest for braking the motor of the apparatus so that the motor will remain inactive so long as the sound box is in position upon its rest.

35 A further object of the invention is to so construct the means above referred to that the motor will be automatically set in operation immediately upon lifting of the sound box from its rest so that the mechanism 40 constitutes means for automatically starting the motor as well as means for automatically stopping the same.

45 A further object of the invention is to so construct the mechanism that the same will not in any way interfere with the reproduction of the tones nor in any way interfere with or retard the action of the motor or any other portion of the reproduction apparatus per se.

50 A still further object of the invention is to so construct the automatic starting and stopping mechanism that the same may be conveniently embodied in the construction of practically all standard types of sound reproduction apparatus.

In the accompanying drawings:

Figure 1 is a side elevation of the mechanism embodying the present invention;

Fig. 2 is a rear elevation of the mechanism;

Fig. 3 is a top plan view of the mechanism;

Fig. 4 is a view similar to Fig. 3 but illustrating the parts in another position;

Fig. 5 is a detail vertical transverse sectional view through a portion of the mechanism.

In the drawings the numeral 1 indicates the baseboard of the reproducing apparatus which ordinarily constitutes the top of the 70 usual box in which the motor of the apparatus is housed, and the numeral 2 indicates the rotary turntable which is to support the disk record, the shaft for supporting and imparting rotary motion to this table being 75 indicated by the numeral 3 and being driven by the motor which is indicated in general in the drawings by the numeral 4 but which is not illustrated in detail inasmuch as in itself it constitutes no part of the present invention. However, this motor includes the usual governor shaft indicated in general by the numeral 5 and this shaft, for the purposes of the present invention, has fixed 80 upon it a brake element which in the present instance is in the nature of a disk 6 although this element may be in the nature of a wheel, drum, or cylindrical enlargement upon the shaft. The motor frame is indicated in general by the numeral 7 and the same supports 85 the frame in which the mechanism of the present invention is mounted, this latter frame being indicated in general by the numeral 8. Rotatably mounted in suitable bearings in the frame 8 is a shaft 9 upon 90 one end of which is fixed any suitable type of gear element 10 driven either from the drive gear of the motor indicated by the numeral 11 or from any other arrangement of gearing. Thus when the 100 motor is operating, rotary motion will be imparted to the said shaft 9. This shaft, for a purpose to be presently described, has fixed upon it at its other end a disk 12 provided upon one face with an annular series of cam lugs 13 which may, if desired, be struck out from the material of the disk, the outer sides or faces of the said lugs being all inclined in the same direction with relation to the direction of rotation of 110

105

the disk. Upon the opposite face of the disk there is provided an annular series of laterally projecting studs or pins 14 and each of these studs or pins is located at a point opposite the inner end or low point of a respective one of the cam lugs 13 as clearly shown in Figs. 1, 3 and 5 of the drawings.

The tone arm of the reproducing apparatus is indicated in general by the numeral 15 and that portion of the said arm which extends below the board 1 is indicated by the numeral 16, the arm being provided with the usual swivel connection or bearing 17 in the board 1 so as to adapt the arm to swing laterally and therefore permit it to follow the record groove as the stylus travels therein, the sound box being indicated by the numeral 18 and the said stylus by the numeral 19. The connection 17 is movable with the tone arm 15 in the swinging movement of the latter and this connection is provided beneath the board 1 with a collar 20 having a circumferential groove 21. The numeral 22 indicates a drag arm provided at its inner end with an annular friction collar 23 split at a point in its periphery as indicated by the numeral 24, this collar being frictionally seated within the groove 21 in the collar 20, as clearly shown in Figs. 1 and 4 of the drawings. It will be evident at this point that as the stylus travels in the record groove and is carried toward the center of the record, the tone arm 15 will be gradually swung in the corresponding direction and due to the frictional engagement of the collar 23 of the arm 22 with the collar 20 of the tone arm, the said arm 22 will likewise be urged in such direction although due to the frictional connection between the arm 22 and the tone arm, this tendency toward movement of the arm 22 with the tone arm may be overcome, and in fact is intermittently overcome in the operation of the mechanism of the present invention as will be presently made clear.

The numeral 25 indicates an actuating lever which is mounted as at 26 upon the frame 8 for lateral oscillatory motion, this lever being provided near its pivoted end 50 with a lateral arm 29 which projects through a slot or opening 30 formed in the said frame 8 and which is provided at its end with an upstanding pin 31 engaging between spaced fingers 32 formed by bifurcating the free end of the drag arm 22. At its free end the actuating lever 25 is bifurcated to form spaced fingers one indicated by the numeral 33 and the other by the numeral 34, these fingers lying at opposite sides of the disk 12, 60 as clearly shown in Figs. 3 and 4 of the drawings and being, generally speaking, respectively in the path of movement of the cam lugs 13 and trip pins 14.

The numeral 35 indicates a brake lever 65 which is pivotally mounted as at 36 upon

the frame 8 and which carries between its ends a brake block or shoe 37 of felt or other suitable material designed, when the lever is swung upwardly, to be brought into engagement with the lower side of the periphery 70 of the brake disk 6, as clearly shown in Fig. 1 of the drawings. Near its free end the brake lever 35 works in a slot 38 formed in an outstanding bracket portion 39 upon the frame 8, and adjacent this point the actuating lever 25 is provided with a lifting finger 40 projecting from its upper side and having a transverse engaging upper end 41 located directly beneath and designed to be brought into engagement with the brake 80 lever 35 under conditions to be presently explained, the actuating lever 25 being resilient whereby it may be sprung upwardly as well as having the lateral oscillatory motion heretofore referred to.

The numeral 42 indicates a trip lever which is pivotally mounted as at 43 upon the frame 8, and one end of this lever extends between the free ends of the brake lever 35 and actuating lever 25, as clearly shown in 90 Figs. 1 and 5 of the drawings, this end of the lever being indicated by the numeral 44 and the lever being provided at its said end with a downwardly projecting trip finger, indicated by the numeral 45. A spring 46, 95 is connected to the lever near its other end, and to the under side of the board 1 and yieldably supports the last mentioned end of the lever in elevated position. Pivotally connected at its lower end to the said last 100 mentioned end of the lever, as indicated by the numeral 47, is a rod 48 which at its upper end is provided with a head 49 constituting a rest for the sound box 18, the rod 48 fitting slidably through the baseboard 1 and 105 being normally supported in elevated position through the said lever 42 and the spring 46.

The operation of the mechanism is as follows: When the reproducing apparatus is 110 not in use, the sound box 18 or its stylus 19 is disposed upon the rest 49, as shown in Fig. 1 of the drawings and the weight thereof will result in the rod 48 being depressed thus swinging the corresponding end of the trip 115 lever 42 downwardly against the tension of the spring 46 and swinging the other end 44 of the said lever upwardly and into engagement with the outer end of the brake lever 35. In this manner the brake lever is swung 120 upwardly so as to bring its shoe 37 into braking engagement with the disk 6 and the motor is restrained from operation. As soon, however, as the sound box is removed from the rest 49 as for example when it is lifted 125 immediately prior to the playing of a record, the spring 46 will act to swing the end of the lever 42 to which it is connected upwardly, swinging the opposite end of the lever downwardly and thus permitting the 130

brake lever 35 to swing in a downward direction carrying the shoe 37 out of engagement with the disk 6 and permitting the motor to operate. It will be evident therefore 5 that so long as the sound box is in position resting upon the rest 49, the motor will be restrained from operation and that as soon as the sound box is lifted from the rest the motor will be automatically set in operation.

10 Assuming that the sound box has been lifted from the rest and has been positioned with its stylus 19 engaging in the record groove, the stylus will be carried gradually toward the center of the disk as it travels in 15 the groove, and consequently there will be a gradual inward swinging movement of the tone arm 15 together with the collar 20 carried thereby. This will tend to impart corresponding movement to the drag arm 22 20 and as a result this arm, through coaction of its fingers 32 with the pin 31, will exert a drag upon the extension 29 of the actuating lever 25 to swing the said lever inwardly so that its finger 33 will be positioned in the 25 path of movement of the cam lugs 13. As each of these lugs passes the finger 33, it will act against the finger to swing the actuating lever 25 upon its pivot in an outward direction to bring the finger 34 thereof into the 30 path of movement of the trip studs 14. In this movement of the lever 25, the drag arm 22 will, of course, be correspondingly moved through coaction of the pin 31 with the fingers 32 of the said drag arm, the frictional 35 force normally providing for movement of the arm 22 with the tone arm being overcome. As soon, however, as each lug 13 passes the finger 33, the tone arm in continuing its inward swinging movement and carrying with 40 it the drag lever 22 will return the actuating lever 25 to its original position by swinging the said lever inwardly so that again the finger 33 will be brought into the path of movement of the cam lugs and the finger 34 45 will be brought to position out of the path of movement of the studs or trip pins 14. This operation will continue so long as the stylus is traveling in the spiral length or rod groove but as soon as the stylus reaches the 50 inner end of the groove it will no longer be carried inwardly toward the center of the record and consequently the tone arm 15 will cease its inward swinging movement. Therefore, the drag arm 22 will no longer be actuated to return the actuating lever 25 to the 55 position shown in Fig. 4 in which position the finger 34 will clear the trip pins 14, but the said actuating lever 25 will, on the other hand, remain in the position shown in Fig. 60 3 of the drawings. Then as one of the trip pins 14 is brought into engagement with the finger 34, the actuating lever 25 will be sprung upwardly so that the lifting finger 40 will engage beneath the brake lever 35 65 and swing the said lever upwardly to brak-

ing position. At this time the parts will be in the position shown in Fig. 5 of the drawings, the trip finger 45 being located close to the outer edge of the actuating lever 25, and the inner end of the trip lever 42 being in lowered position. If now the sound box is lifted from the record and the tone arm is swung to inactive position and the sound box is disposed upon the rest 49, the rod 48 will be depressed thereby rocking the lever 42 so as to swing its inner end upwardly. In this movement of the lever the finger 45 will ride against the outer edge of the actuating lever 25 and swing this lever upon its pivot so as to disengage the finger 34 from the stud or pin 14 by which it has been elevated in the rotation of the disk 12. Thus the lever 25 will be released for return to the position shown in Fig. 1 of the drawings but the inner end of the lever 42 will continue in its upward movement until it has engaged and lifted the outer end of the brake lever 35 thus bringing the shoe 37 into braking engagement with the brake disk 6.

Having thus described the invention, what is claimed as new is:

1. In stop mechanism for sound reproduction apparatus, the combination with a movable tone arm, and a motor including a brake element, of a brake element supported to assume by gravity a position out of coactive relation to the first mentioned brake element, and means operable to automatically move the gravity actuated brake element into coactive engagement with the first mentioned brake element upon cessation of movement of the tone arm.

2. In stop mechanism for sound reproduction apparatus, the combination with a member movable in consonance with the travel of the stylus of the apparatus, and a motor including a brake element, of a brake element for coaction with the motor brake element and normally assuming by gravity a position out of coactive relation thereto, a rotary element driven from the motor, an actuating member for the second mentioned brake element, means upon the rotary element for coaction with the actuating member to move the latter into coactive engagement with the second mentioned brake element, and operative connection between the actuating member and the said member which is movable in consonance with the travel of the stylus to effect movement of the actuating member in a manner to provide against operation of the actuating member through rotation of the said rotatable element.

3. In stop mechanism for sound reproduction apparatus, the combination with a motor and a member movable in consonance with the travel of the stylus of the apparatus, of a rotatable member driven by the motor and provided upon one face with a

- trip element and upon its other face with a cam element, an actuating lever having portions lying at opposite sides of the said rotatable member whereby in the rotation of 5 the member the cam means will shift the actuating member, operative connection between the operating member and the member which is movable in consonance with the travel of the stylus tending to move the 10 said actuating member to position out of coactive relation to the said trip element, and a brake element for actuation by the actuating element when the latter is engaged by the trip element.
- 15 4. In stop mechanism for sound reproduction apparatus, the combination with a motor, of coacting brake elements, means for automatically actuating the same, a reproducer rest depressible by the weight of 20 the reproducer when in position thereon, and means operable to automatically effect coaction of the said brake elements upon depression of the said rest.
- 25 5. In stop mechanism for sound reproduction apparatus, the combination with a 30 motor and an element of the reproduction apparatus, of a depressible rest of said element, means operable to automatically restrain the motor from operation upon depression of said rest when the weight of 35 the element is imposed thereon and also operable on cessation of reproducing movement of the said element.

6. In stop mechanism for sound reproduction apparatus, the combination with a 35 motor including a brake element, of a yieldably supported reproducer rest, a brake element for coaction with the first mentioned brake element, operative connection between the said rest and the second mentioned brake element for moving the latter into coactive relation to the first mentioned brake element when the said rest is depressed by the weight of the reproducer, and motor actuated means for operating the 40 45 brake elements.

In testimony whereof I affix my signature.

FRANK J. FRAZEE. [L. s.]
